BY *E. E. Rodabaugh*
ATTORNEY.

UNITED STATES PATENT OFFICE.

JOHN W. KYLE, OF SAN DIEGO, CALIFORNIA.

LIFE-NET HOLDER.

1,020,146.

Specification of Letters Patent.

Patented Mar. 12, 1912.

Application filed April 17, 1911. Serial No. 621,697.

To all whom it may concern.

Be it known that I, JOHN W. KYLE, a citizen of the United States, and a resident of San Diego, in the county of San Diego and State of California, have invented certain new and useful Improvements in Life-Net Holders, of which the following is a specification, reference being had therein to the accompanying drawings.

10 My invention relates to a life net holder for holding nets and to be used more particularly for holding one or more of the sides of a life net such as is used for rescuing persons from a burning building or other buildings when it is impossible or impracticable for the inmates to escape from the same by the usual means of egress.

The objects of my invention are to provide a device of the character described, that 20 may be quickly and easily attached to the outer wall of a building from which the people are to be rescued, which may also be quickly attached to and which will give a proper amount of elasticity to the net, so 25 that a person striking it will not be injured, and further which is simple, durable and economical of construction. I attain these objects by the device illustrated in the accompanying drawings, in which:—

30 Figure 1 is a front elevational view of a building, showing my device attached to the wall of the building, and to the life net, Fig. 2 is a side elevational view of the same, Fig. 3 is an enlarged end view of my device 35 showing the hook, the cable, the spring and a life net attached thereto, and Fig. 4 is an enlarged front view of my device showing it attached to the wall of a building and connected with a life net.

40 Similar characters of reference refer to similar parts throughout the several views:—

The holder is composed of hooks 1, cable 2, rod 3, springs 4, and rod 5. The hook 1 is preferably made as shown best in Fig. 3 and 45 is adapted to be placed in the walls of buildings a sufficient height from the ground and at a proper distance apart to provide a proper support. The cable 2 is made of a flexible material and is provided with snaffle hooks 6 which are adapted to be attached

to rod 3. In one edge of the life net is securely fastened rod 5 and attached to the rods 3 and 5 are coil springs 4 of which a sufficient number are used to properly support the net and relieve the shock when a body strikes it.

In use the cable is placed on the hooks as shown best in Figs. 1 and 4, and are then attached to rod 3. Rod 3 may be permanently connected by springs 4 to rod 5 or if desired, the springs may be provided with proper hooks for attaching thereto. The outer edge of the net is held by persons, while the inner portion is supported by rod 5, thus forming a safe and substantial support for the life net.

It will be readily seen that with this construction and arrangement, there is provided a life net holder that may be quickly and easily attached to the outer wall of a 70 building, that can also be quickly attached to a life net, that is durable and will furnish a proper amount of elasticity to the net, and that is simple and economical of construction.

Having thus described my invention what I claim as new and desire to secure by Letters Patent is:—

1. A life net holder comprising a rod securely attached to the one edge of a life 80 net, a plurality of coiled springs attached at one of their ends to said rod, another rod attached to the other ends of said springs, a plurality of hooks securely fastened to the wall of a building, a cable adapted to be 85 loosely supported by said hooks, a plurality of snaffle hooks connecting said cable with said last mentioned rod adapted to slide along said cable and rod to provide adjustment of said net to said wall or building, all 90 substantially as set forth.

2. In combination with a life net, a life net holder comprising a rod securely attached to said life net, another rod parallel thereto and spaced apart therefrom, a plurality of springs connecting said rods, a cable adapted to be attached to and carry said last named rod, snaffle hook means 95 slidably mounted on said cable adapted to facilitate its attachment to and removal from said 100

rod and for adjusting said net relatively to said building, and a plurality of hooks securely mounted in the wall of a building and adapted to engage with said cable and support the same, all substantially as set forth.

In testimony whereof, I have hereunto

subscribed my name in the presence of two subscribing witnesses.

JOHN W. KYLE.

Witnesses:

MARY A. BOWMAN,
JOHN S. SIEBERT.
